UNITED STATES PATENT OFFICE

155,903

DESIGN FOR A VACUUM CLEANER OR
SIMILAR ARTICLE

George M. Kelly, Sturgis, Mich., assignor to Douglas Manufacturing Company, Bronson, Mich., a corporation of Michigan

Application September 4, 1948, Serial No. 148,473

Term of patent 14 years

(Cl. D9—2)

To all whom it may concern:

Be it known that I, George M. Kelly, a citizen of the United States, and a resident of the city of Sturgis, in the county of St. Joseph and State of Michigan, have invented a new, original, and ornamental Design for a Vacuum Cleaner or Similar Article, of which the following is a specification, reference being had to the accompanying drawing, forming a part thereof.

In the drawing:

Figure 1 is an elevational view of the vacuum cleaner or similar article, showing my new design; and

Figure 2 is a perspective view thereof.

I claim:

The ornamental design for a vacuum cleaner or similar article, as shown.

GEORGE M. KELLY.
